UNITED STATES PATENT OFFICE.

PHILIP F. SWART, OF ROCHESTER, NEW YORK, ASSIGNOR TO HOMER M. SWART, OF ROCHESTER, NEW YORK.

CASTER.

Application filed July 14, 1917. Serial No. 180,565.

To all whom it may concern:

Be it known that I, PHILIP F. SWART, a citizen of the United States, residing at Rochester, in the county of Monroe and 5 State of New York, have invented a new and Improved Caster, of which the following is a specification.

My invention relates to infants' beds of the knock down or folding type and more 10 particularly to a caster for a bed of such character, an object of the invention being to provide a caster or supporting wheel adapted, when in inoperative position, to lie within and parallel to the base of the bed.

15 The accompanying drawings illustrating my invention are as follows:—

Figure 1 is a side elevation of a folding bed, a portion of the side thereof toward the observer being broken away; Fig. 2, an end 20 view as seen from the right of Fig. 1; Fig. 3, an enlarged end view showing the bed in its folded or knocked down condition; Fig. 4, a plan view from the under side with the sides and ends opened out but with the supporting wheels swung to inoperative position, a portion only of the springs and mattress being shown; Figs. 5 and 6, enlarged 25 top plan view and elevation, respectively, of a corner of the base member showing details of construction to be explained; and Fig. 7, a vertical sectional view taken along the line 1—1 of Fig. 1 but showing the hinged upper side section in its lowered position.

35 Similar reference characters refer to similar parts throughout the several views.

The bed comprises a rectangular base or body portion 1 for containing the springs 2 and mattress 3 and having side and end 40 walls. To such side walls there are connected by hinges 4 the front and rear side frame members 5 and 6, respectively, while to the end walls are similarly connected the end frame members 7, all of such members 45 having perforated panels therein, preferably of wire screen, which provide for plenty of ventilation. These sides and ends are adapted to fold inwardly and when closed to occupy the relative positions in 50 which they are seen in Fig. 3, the end members 7 being on the bottom and against the mattress 3, then the side member 5 and with the other side member 6 upon the top.

When the bed is open and ready for occupancy the sides 5 and 6 overlap the ends 7

and all four members are securely held in upright position by latches 8, which are pivotally connected to plates 9 secured to the sides and near the tops of the end frame members 7 and slotted at their outer ends to 60 engage over studs 10 carried by plates 11 secured on the end edges of the side frame members.

In order that a child may more easily be 65 lifted into and out of the bed, the side member 5 is formed in two longitudinal sections 12 and 13 and connected by hinges 14, both such sections being held by latches 8, as above described, to the end members 7 independently of each other so that the top section 12 when released may be swung outwardly and dropped to the position in which it is seen in Fig. 7.

Secured to the bottom of the base 1 are 70 plates 19 extending diagonally across the corners thereof and these plates have upwardly extending reinforcing members 20 secured by screws to the inner faces of the side and end walls of the base. Upon the plates 19 there is supported an angle iron 75 frame 21 comprising the supporting means for the springs 2 which are of the flat interwoven wire type, as indicated in Figs. 4 and 7, and connected to the said frame by links 22. The mattress 3 rests upon the springs 2 80 and the top thereof comes substantially in line with the lower edges of the end frame members 7, thus permitting such members 85 to be dropped to folded position.

The supporting wheels or casters 23 are of 90 comparatively large diameter as it is preferable that the mattress be supported several inches above the floor, and it is one of the main objects of my invention to so pivotally connect these wheels to the base 1 in a way 95 that when the sides and ends are folded the wheels, also, can be folded, that is,—swung to occupy a position flat against the springs 2, as seen in Fig. 4, thereby permitting the bed being more easily carried from place to 100 place and causing it to occupy considerably less space in transportation and in storage than it otherwise would.

Each of the plates 19 has a centrally disposed slot 24 extending inwardly from one 105 edge for receiving the shank of a T-bolt 25 the head of which is pivoted in bearings 31 formed on the upper face of the plate and adjacent the sides of such slot. These bolts 25 are adapted to swing into and out of their 110

respective slots 24 and to be locked when extending outwardly and through the slots, as in Fig. 6, by latches 26 pivoted at one end to the projections 27 extending rearwardly from the plates 19 and slotted near their centers to engage the bolts, such latches being disposed between the bottom of the plates 19 and shoulders 28 formed on the bolts. Loosely mounted on the bolts below the shouldered portions 28 are the heads 29 of forks 30 between the outer ends of which are mounted the supporting wheels 23. In Figs. 5 and 6 the bolt 25 is shown in its unlocked and locked positions, respectively, the wheel and forks being removed. It will be seen that, when the latches 26 are released and the bed tipped upon its side, the bolts 25 can be swung substantially ninety degrees in planes at right angles to the bottom of the base 1, and that with the heads 29 freely revoluble on the bolts the wheels can be turned to lie flat against the springs, as in Fig. 4.

What I claim is:

- 25 1. In combination with a base, a slotted supporting plate on the under side of the base, a bolt normally extending through said slot and pivoted on the plate to swing inwardly to an inoperative position parallel with the bottom of the base, a swivel wheel mounted on said bolt, and a pivoted latch movable across the face of said plate to hold the bolt in operative position.
- 30 2. In combination with a base, a slotted supporting plate on the under side of the base, a **T**-bolt normally extending through

said slot and pivoted on the plate to swing inwardly to an inoperative position parallel with the bottom of the base, a swivel wheel mounted on said bolt, and means for holding 40 said bolt in operative position comprising a pivoted latch movable across the face of said plate and having a notch for receiving the bolt.

3. In combination with a base, a slotted 45 supporting plate on the under side of the base, a **T**-bolt normally extending through said slot and pivoted on the plate to swing inwardly to an inoperative position parallel with the bottom of the base, a shoulder on 50 said bolt, a swivel wheel mounted on said bolt, and means for holding said bolt in operative position comprising a pivoted latch movable across the face of said plate, engaging between the plate and the said shoulder 55 and having a notch for receiving the bolt.

4. In combination with a base, a slotted supporting plate on the under side of the base, reinforcing members extending upwardly from the plate and secured to the 60 base a **T**-bolt normally extending through said slot and pivoted on the plate to swing inwardly to an inoperative position parallel with the bottom of the base, a shoulder on 65 said bolt, a swivel wheel mounted on said bolt, and means for holding said bolt in operative position comprising a latch pivoted to the plate and movable across the face thereof, such latch engaging between the plate and said shoulder, and having a notch 70 for receiving the bolt.

PHILIP F. SWART.
